VENETIAN BLIND BRACKET

Harry Nelson, New York, N. Y., assignor to
 Lorentzen Hardware Mfg. Corp., New York,
 N. Y., a corporation of New York

Application October 23, 1945, Serial No. 623,970

12 Claims. (Cl. 248—264)

1

This invention relates to Venetian blinds, and more particularly to so-called installation brackets which are affixed to the window frame for supporting the head-bar of a Venetian blind.

In mounting Venetian blinds it is a common practice to make use of a suspension bar or "head-bar," which supports a tilt bar and which carries certain mechanism for operating the blind. The head-bar is commonly mounted on brackets placed on opposite sides of the window frame, and it is desirable to provide the bracket with means for supporting a valance which serves to conceal the operating mechanism of the blind. In the case of a so-called "inside" mounting of the blind the installation brackets are affixed to the sides of the window jambs. In the case of a so-called "outside" mounting of the blind the installation brackets are affixed to the front faces of the jambs.

A general object of the present invention is to so simplify and improve the construction of Venetian blind installation brackets as to effect economies in manufacture and facility of installation, while providing adequate strength and durability.

Another object of the invention is to provide a bracket of the character mentioned which can be economically and satisfactorily made from sheet metal that has received rust-proofing treatment.

Another object of the invention is to provide a sheet metal bracket of the character described which can be rapidly and economically manufactured without welding.

Another object of the invention is to provide a bracket of the character described which has an improved, smoothly operating, locking device for securing the head-bar in position.

A further object of the invention is to provide a Venetian blind installation bracket in which the weight of the supported blind aids in more securely holding the valance carrier in place.

A still further object of the invention is to provide a Venetian blind installation bracket of such construction that it will have adequate rigidity and strength when made of stamped sheet metal of lighter gage than heretofore used for such brackets.

Various additional objects will be apparent from the detailed description which follows.

2

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

Fig. 1 is a plane development of the body member of the bracket.

Fig. 2 is a side elevation of the body member of the bracket.

Fig. 3 is a plane development of a slider used in the bracket to retain the head-bar in position thereon.

Fig. 4 is an isometric view of the slider.

Fig. 5 is a perspective view of the bracket with the valance holder in open position.

Fig. 6 is a vertical section on line 6—6 of Fig. 7, showing the head-bar, valance, and a portion of the jamb in section, and showing the bracket in side elevation.

Fig. 7 is a section on line 7—7 of Fig. 6.

Fig. 8 is a section of the bracket on line 8—8 of Fig. 6, fragments of the head-bar and valance being indicated in dot-dash lines.

Fig. 9 is a plane development of the valance holder.

Fig. 10 is a side elevation of the valance holder.

Fig. 11 is a section through the valance holder on line 11—11 of Fig. 10.

The drawings show a right-hand bracket embodying the present invention, i. e., a bracket for supporting the right-hand ends of the head-bar and valance as viewed from the room side of the

window. It will be understood that a left-hand bracket also is used with each Venetian blind to support the left-hand ends of the head-bar and valance, and that the left-hand bracket is of the same construction but of the opposite hand.

It is very desirable in brackets for Venetian blinds that they be protected against disfigurement through rusting, but steel which has been "bonderized" or otherwise "rust-proofed" does not respond well to spot-welding for the reason that the protecting surface layer may interfere

with proper formation of the welded joint. To fabricate parts by riveting is undesirably slow and expensive for quantity production. I have, therefore, devised a bracket for the purpose described which consists of three unitary parts, each consisting of a single piece of sheet metal (preferably steel) and each of which may be satisfactorily fabricated on a production basis without welding or riveting. These parts may be formed from sheet steel by any suitable stamping and pressing operations of types known in the art of stamping sheet metal.

Reference will now be had to Figs. 1, 2, 5, 6, 7 and 8 of the drawings. The body member of the bracket, designated as a whole by 1, is a one-piece sheet metal stamping having a vertical plate portion 2, a mounting flange 15, and a head-bar supporting shelf 3 which extends horizontally from a depending portion 11 that lies alongside of the upper part of the plate portion 2. Plate portion 2 is provided with a plurality of holes 9 (three shown) to receive screws for an "inside" mounting of the blind. Plate portion 2 is also provided with a hole 5 to receive a rivet for pivotally securing the valance holder to the body member of the bracket.

Mounting flange 15 lies in a vertical plane at right angles to plate portion 2, being connected to plate portion 2 by a right-angle bend at line 8 (Fig. 1). Diagonally extending stiffening ribs 30 are pressed out at 18, 18 to brace the mounting flange with respect to plate portion 2. A number of holes 10 (four shown) are provided in the mounting flange 15 to receive screws for a so-called "outside" mounting of the blind. Preferably the mounting flange 15 terminates above the lower edge of plate portion 2 and has its rear face flush with edge 2a (Fig. 2) as explained near the beginning of page 2 of the specification of my U. S. Patent 2,281,043 dated April 28, 1942.

Depending portion 11 is connected with plate portion 2 by a bend of small radius at line 6 (Fig. 1). Preferably the bend is so made that the lower part of portion 11 engages plate portion 2 with resilient pressure. Shelf 3 is connected with portion 11 by a bend of small radius at line 7 (Fig. 1). A plurality of stiffening ribs 4-4' (three sets shown) are pressed out from portion 11 and shelf 3. Portion 11 is provided with a rectangular slider opening 12 from the lower edge of which there projects a spring finger 14 adapted to bear against the slider as will be explained later. Portion 11 is also provided with a moon-shaped cutout at 16 (Fig. 1) to provide clearance for the insertion of a screw through upper hole 9.

A slider, designated as a whole by 20 (Figs. 4, 3, 5, 6, 8 and 7) is formed as a one-piece sheet metal stamping. It includes a vertical body portion 19, a horizontally extending retainer finger 24, bearing wings 21, 21, detents 22, 22, and cam-like entrance projections 23, 23. Portions 21, 22, 23 and 24 all extend at right angles to body portion 19, portion 24 lying in a horizontal plane and portions 21, 22 and 23 lying in vertical planes when the bracket is mounted.

The slider of Fig. 4 is assembled with the body member of Fig. 2 by simply placing it in upright position, in opening 12 of portion 11 and then forcibly depressing it. Entrance projections 23, 23 cam the lower part of depending body portion 11 away from the plate 2; and after detents 22, 22 have passed beneath shelf 3, body portion 11 snaps back against plate 2, thereby

retaining the slider in assembled relation to body member 1.

A valance carrier, designated as a whole by 27, (Figs. 10, 11, 9, 5, 6, 8 and 7) is formed as a single sheet metal stamping. It includes a front flange portion 31 and a side flange portion 28 connected by a bend of appreciable radius in zone 26. Side flange 28 is offset as shown to provide a shoulder at 29 which, in the closed position of the valance holder (Fig. 8), engages the forward vertical edge of plate 2. A raised circular portion 33 is pressed from the metal of flange 28 and pierced at 34 to receive a rivet 36 (Fig. 7) for pivotally attaching the valance holder to plate 2. Also a rib 37 is pressed from flange 28 to snap behind the foremost rib 4 of depending body portion 11 to hold the valance carrier in closed position. Yielding fingers 38, 39 are adapted to engage the valance 32, top and bottom, and hold it against front flange 31. The valance is supported at the bottom by a finger 35.

With the bracket assembled as shown in Figs. 5 and 6 and mounted in a vertical position on a window frame, the slider 20 is elevated to its uppermost position preparatory to receiving a head-bar such as bar 25. Upward movement of the slider is arrested by detents 22, 22 striking the bottom of shelf 3, in which position finger 24 will be sufficiently elevated to permit the head-bar to be slid onto shelf 3. While the head-bar is being placed in position, the slider is held in elevated position by spring finger 14 which frictionally engages it. With the head-bar in position, the slider is pulled down, bringing retainer finger 24 to or near the bottom of groove 26 in the head-bar and thereby holding the head-bar in position on shelf 3. In elevating or depressing slider 20 it is not necessary to have access to the retainer finger 24 as the slider can be manipulated by a pointed instrument inserted into hole 19a or by a screwdriver placed against detents 22, 22 or projections 23, 23. Bearing wings 21, 21 not only guide the slider smoothly in opening 12, but staunchly support the slider when forward or backward force is imposed on an installed head-bar.

Individual rivets 36 may vary somewhat in length when set, but raised portion 33 is sufficiently yieldable to take care of such variations and afford a lasting snug attachment of the valance carrier 27 to plate 2 without the use of a spring washer or the like. The valance 32 is slid into the carrier 27 from the open end of the carrier and yieldable fingers 38, 39 hold the valance snugly against flange 31 despite considerable variation in thickness of the valance. Since one of the fingers 38 is close to finger 35 there is no danger of even a very thin valance being forced into such a position that it will drop past finger 35. The fingers 38, 39 are pressed out in such manner as to leave the free edge of flange 28 uninterrupted from bottom to top. Thus there is no danger of this flange catching on the forward edge of plate 2 or straddling it, as the valance carrier is closed. In open position of the valance carrier, a portion of shoulder 29 engages the bottom edge of plate 2 and prevents the carrier 27 from swinging lower than the position shown in Fig. 5.

Body members 1 may be made with the shelf 3 at different levels, to receive head-bars of different vertical dimensions. The length of rib 37 on the valance carrier is sufficient to enable it to snap behind the foremost vertical rib 4 on depending body portion 11 for the various com-

mercial levels of shelf 3. Thus, a single size and style of valance carrier suffices for assembly with body members 1 intended to receive head-bars of different vertical dimensions. The resiliency of depending body portion 11 is sufficient to hold the valance carrier in closed position unless the valance carrier is forcibly opened. However, the weight of the blind imposed on shelf 3 further presses the lower part of depending portion 11 against plate 2, thereby aiding in holding the valance carrier in closed position. This is particularly advantageous in the case of wide windows, which require a very long valance board.

Shelf 3 may optionally be provided with upwardly extending burrs or projections 3a, 3a struck from the edge metal of the shelf, and/or with a hole 3b. Burrs 3a, 3a, when provided embed themselves in the head-bar as shown in Figs. 6 and 7 and effectively resist horizontal shifting of the head-bar on the shelf. To secure the head-bar against movement in any direction with respect to the shelf, a screw may be inserted upwardly therein through hole 3b. In this case slider 20 may, if desired, be omitted.

What I claim is:

1. A Venetian blind bracket having a body member formed of a single sheet metal plate having a portion folded upon the remainder and stressed at the fold so that the folded portion contacts the plate with resilient pressure, part of said folded portion extending away from the plate to form a supporting shelf at substantially a right angle to said sheet metal plate, said sheet metal plate having a laterally projecting substantially right-angular vertical flange for mounting the bracket on the forward face of a window frame.

2. A Venetian blind bracket having a body member formed of a single sheet metal plate having a portion provided with longitudinal stiffening ribs and a longitudinal slider opening, said portion being folded over upon the remainder of the plate and stressed at the bend so that the folded portion contacts the plate with resilient pressure, the terminal part of said folded portion extending away from the plate to form a stiffened horizontal supporting shelf at substantially a right angle to said plate, and a locking element between said folded portion and said plate slideable in said slider opening to lock a Venetian blind head-bar upon said shelf.

3. A Venetian blind bracket as defined in claim 2 having a pivoted valance carrier adapted to make latching engagement with said folded portion.

4. A Venetian blind bracket having a body member formed of a single sheet metal plate having a portion provided with a longitudinal stiffening rib and folded upon the remainder and stressed at the fold so that the rib of the folded portion contacts the plate with resiliently yieldable pressure, part of said folded portion extending away from the plate to form a stiffened horizontal supporting shelf at substantially a right angle to said sheet metal plate, and a valance carrier pivoted adjacent the lower forward corner of said body member and swingable into open and closed position and having a portion which abuts against the forward edge of the bracket when the valance carrier is in closed position, and having a boss which snaps past said rib on the folded portion of the bracket between the folded portion and said plate to hold said valance carrier in closed position.

5. A Venetian blind bracket having a body

member formed of a single sheet metal plate having a portion provided with a longitudinal slider opening with a resilient tongue projecting from one end of said opening, said portion being folded over upon the remainder of the plate and stressed at the fold so that the folded portion contacts the plate with resilient pressure, the terminal part of said folded portion extending away from the plate to form a substantially horizontal supporting shelf, and a locking element between said shelf and said plate slideable in said slider opening and pressed against the plate by the resilient tongue.

6. A Venetian blind mounting as defined in claim 5 in which the locking element is formed of a sheet metal stamping having edge flanges which constitute bearings in said slider opening, and other edge flanges which constitute projections for manipulating said locking element and retaining it in said mounting.

7. A Venetian blind installation bracket comprising: a body member having a head-bar-supporting shelf yieldably attached to the remainder of the body member, and a head-bar retaining slider movable up and down with respect to the shelf, the slider having projecting means for retaining it in assembled relation to said body member, and the shelf yielding in its relationship to the remainder of the body member by an amount at least equal to the thickness of the slider and providing for assembly of the slider with the body member.

8. A Venetian blind bracket as in claim 7 in which the slider has a cam-like projection operative to shift the shelf away from the remainder of the body member as the slider is telescoped into assembled relationship with the body member.

9. A Venetian blind bracket as in claim 7 in which the body member is provided with a guideway in which the slider reciprocates and the slider is provided with wings engageable with the opposite sides of the guideway.

10. A Venetian blind installation bracket comprising: a body member having a head-bar-supporting shelf yieldably attached to the remainder of the body member, a valance carrier swingably attached to the body member for movement into closed position with a portion of the carrier between said shelf and the remainder of the body member, the shelf yielding in its relationship to the remainder of the body member by an amount at least equal to the thickness of said portion of the carrier, and latching means for holding the carrier in closed position, said latching means including a latching element on said carrier.

11. A Venetian blind bracket having a body member formed of a single sheet metal plate having a portion folded upon the remainder and stressed at the fold so that the folded portion contacts the remainder of the plate with resilient pressure, part of said folded portion extending away from the plate to form a supporting shelf at substantially a right angle to said sheet metal plate, and a valance carrier pivoted on a forward corner of the plate and swingable between open and closed position and having a portion entered between the folded portion and the remainder of the plate when the retainer is in closed position.

12. A Venetian blind bracket having a body member formed of a single sheet metal plate having a portion folded upon the remainder and stressed at the fold so that the folded portion contacts the remainder of the plate with resilient

pressure, part of said folded portion extending away from the plate to form a supporting shelf at substantially a right angle to said sheet metal plate, and a valance carrier having a flange superimposed on and pivotally connected with the plate at one of its forward corners, said retainer being swingable between open and closed position and the superimposed flange thereof entering between the folded portion and the remainder of the plate when the retainer is in closed position.

HARRY NELSON.
